(57) **CLAIM**

The ornamental design for a jewelry holder, as shown and described.

DESCRIPTION

The jewelry holder is a rectangular rack with various projections and features for holding articles of jewelry.

FIG. 1 is a perspective view of the jewelry holder.

FIG. 2 is an enlarged view of the jewelry holder, taken from within circle 2 in FIG. 1, more clearly showing the detail of the holder's upper corners.

FIG. 3 is a left plan view of the jewelry holder.

FIG. 4 is a front plan view of the jewelry holder.

FIG. 5 is a right plan view of the jewelry holder.

FIG. 6 is a rear plan view of the jewelry holder; and,

FIG. 7 is a top plan view of the jewelry holder.
